Inventor

GUSTAV A. SWENSON

By his Attorney

Abel L. Brownrigg

UNITED STATES PATENT OFFICE.

GUSTAV A. SWENSON, OF BROOKLYN, NEW YORK.

HOISTING GEAR.

Application filed May 21, 1921. Serial No. 471,454.

To all whom it may concern:

Be it known that I, GUSTAV A. SWENSON, a subject of the King of Sweden, residing at Brooklyn, in the county of Kings and State 5 of New York, have invented certain new and useful Improvements in Hoisting Gears, of which the following is a specification:

This invention relates generally to hoisting gear and particularly to a hoist or sling 10 especially adapted for use in handling barrels.

Devices heretofore known and used for this general purpose have been open to the general and serious objection that they have 15 not only been difficult to manipulate, but, in addition, they have not been so constructed as to afford the necessary security against the falling of articles from the hoist with the resulting destruction of goods or 20 danger to the attendants.

It is the general object of this invention to provide a hoist or sling which will be free from the objections referred to, which can be easily and expeditiously manipulated 25 either in placing the device in position on a package preparatory to hoisting, or in releasing the device following the hoisting operation, and which will securely hold the article in any ordinary mishap, such as 30 striking the edge of a hatch, or a part of the structure on a dock or ship's deck.

The invention includes a pair or set of rigid, endless metal loop members formed for ready grappling engagement with the 35 opposite reduced ends of a barrel, the loop members being so fitted to the barrel as to prevent the enlarged mid-portion of the barrel from slipping therethrough. The invention also includes the use of a flexible 40 chain or rope attached to the rigid barrel-grappling loop members by being passed through eyes or reduced loops formed integrally with the grappling members. Other features of the invention will be here- 45 inafter referred to.

In the drawing in which a preferred embodiment of the invention is selected for illustration,

Figure 1 is a view in side elevation of a 50 barrel hoist including the invention and showing a barrel held in place therein.

Figure 2 is a view similar to Figure 1 showing the hoist disconnected from the barrel.

55 Figure 3 is a face view of a barrel-grap-

pling loop member forming part of the invention.

Referring to the drawing, a barrel sling or hoist is shown which is made up of three main parts. A flexible loop 1 formed of 60 chain or rope of any suitable length and adapted to be engaged by the hook 2 forming the terminal of a rope or fall suspended from the hoisting arm of a crane or derrick in an obvious manner. In order to lift 65 or hoist a package such as a barrel 3 the flexible loop 1 is provided with a pair or set of barrel-grappling rings or loops 4 each formed of a single endless piece of rigid metal, such as wrought iron or steel. The 70 barrel-grappling loop members 4 are given a slightly curved formation as seen in side view as will be clear from the drawing in order to thereby obtain a formation of the loop members which will facilitate the 75 expeditious attaching of the loop members in grappling relation to the opposite reduced ends of a barrel or to as quickly disassemble the loops from their barrel-grappling position.

In order to facilitate the attaching of the rigid loop members 4 to the flexible ring or loop 1 the loops 4 are provided with relatively small secondary loops or eye members 5 which are formed by bending two portions of the loop 4 into contact with each other and welding or otherwise attaching them together at the points 6.

The relatively small eye members 5 not only form loops through which the rope 90 or chain 1 can be passed in a permanently connected relation thereto, but the eye members 5 of the loops 4 additionally provide what may be termed handle members by means of which the loops 4 can be readily 95 manipulated by an operator and put in place on a barrel which it is desired to hoist. By seizing each one of the loops 4 at the handle portion 5 the operator can in a single operation place both loops over the opposite ends 100 of the barrel with a minimum of exertion and with a very slight expenditure of time and energy. It will be seen that by the use of the rigid barrel-engaging loops 4 the loss of time which usually exists in the ma-

nipulation of the ordinary rope tackle is wholly done away with and the handling of barrels which must be subjected to a hoisting operation is correspondingly facilitated.

110

Not only is time ordinarily required in the manipulation of barrel hoisting tackle greatly cut down by the use of the rigid loop members 4 in conjunction with the permanently attached flexible chain or rope 1 but the likelihood or danger of the displacement of a barrel from the grappling members during the progress of the hoisting operation is greatly reduced or wholly overcome. In other words, where the contact of a barrel or package with the edge of a hatchway or the striking of the barrel against a part of a ship's superstructure in lifting barrels into or out of the ship's hold, with the consequent dropping of the barrel from its suspended position, and which in prior hoisting practice is a matter of frequent occurrence, is wholly obviated in performing a hoisting operation with the hoisting or lifting sling herein described. The reason for this is that the endless or unbroken rigid loop members 4 have no separable ends which are likely to be opened in experiencing the shock or impact of striking the contained barrel against a rigid part, nor will the pre-formed rigid loop members 4 which are fitted to the diameter of the reduced ends of the barrel allow the barrel to slip through either loop and to fall from its place therein. It will thus be seen that I have provided a barrel sling or hoist which not only can be manipulated with a considerable saving of time or work but by the use of which the factor of safety present in the operation of the hoisting mechanism is greatly increased.

What I claim is:

1. A barrel hoisting device comprising a flexible supporting loop formed for engagement by the lifting hook of a crane, and a pair of rigid endless loop members formed for grappling engagement with the opposite ends of a barrel, portions of said rigid

loop members being attached together to provide eyelet extension members through which said flexible supporting loop is threaded for permanent connection therewith. 45

2. A barrel hoisting device comprising a flexible supporting loop formed for engagement by the lifting hook of a crane, and a pair of rigid endless loop members formed of rod shaped material for grappling engagement with the opposite reduced ends of a barrel, portions of said rigid loop members being attached together to provide eyelet extension and handle members formed integrally with said loop members through which said flexible supporting loop is threaded for permanent connection therewith, and said rigid loop members having a less diameter than the enlarged mid-portion of the barrel. 50 55 60

3. A barrel hoisting device comprising a supporting loop formed for engagement by the lifting hook of a crane, and a pair of rigid endless loop members formed for grappling engagement with the opposite ends of a barrel, each of said rigid loop members being formed at one side into an eye member through which said supporting loop is threaded for permanent engagement therewith, said eye members being formed at an angle to the main body portions of the rigid loop members to thereby form conveniently operable handle members for said grappling loops. 65 70 75

4. A barrel grappling device comprising a rigid metal loop formed of round rod and adapted to be placed over the reduced end of a barrel but having a less diameter than the enlarged mid-portion of the barrel, and a combined eye and handle member formed integrally with said loop. 80

GUSTAV A. SWENSON.
